UNITED STATES PATENT OFFICE.

EDWIN M. SCHANTZ, OF CINCINNATI, OHIO, ASSIGNOR, BY MESNE ASSIGNMENTS, TO UNIVERSAL RECORDER MANUFACTURING COMPANY, A CORPORATION OF ILLINOIS.

RECORDING APPARATUS.

965,754.

Specification of Letters Patent. Patented July 26, 1910.

Application filed November 13, 1908. Serial No. 462,432.

To all whom it may concern:

Be it known that I, EDWIN M. SCHANTZ, a citizen of the United States, residing at Cincinnati, in the county of Hamilton and 5 State of Ohio, have invented certain new and useful Improvements in Recording Apparatus, of which the following is a specification.

The principal object of my invention is to 10 provide apparatus for indicating and recording various circumstances of work done or conditions existing in a factory or other place of business. I employ a strip of paper which is fed slowly past apparatus adapted 15 to mark characters upon the paper. This apparatus is actuated, electrically or otherwise, by machines, indicators, hand-operated and automatic switches, or any of these, so as to give a record on the moving strip of 20 paper of the various events or conditions in the plant which it may seem advantageous to have recorded.

Stated otherwise, the object of my invention is to provide apparatus to synchronously record on a proper medium the various events happening or conditions existing in a plant and furthermore to record such events or conditions in a manner to indicate the proximate reason or cause for any failure 25 in the proper working of the plant, and also to indicate where credit should be given 30 for its successful operation.

My invention resides in the general combination of apparatus to accomplish this 35 purpose, and in the various sub-combinations of apparatus which contribute to the purpose stated.

The objects and nature of my invention will become further apparent on perusal of 40 the following specification and claims, when taken in connection with the accompanying drawings, in which—

Figure 1 is a diagrammatic representation of a factory recording system. Fig. 2 is a 45 record sheet showing the record as kept by my improved apparatus. Fig. 3 is a side elevation of the recording machine. Fig. 4 is a perspective detail of the type anvil. Fig. 5 is a longitudinal vertical section of 50 the recording machine. Fig. 6 is a detail sectional view taken on the line 6 in Fig. 5 looking in the direction of the arrow. Fig. 7 is a top plan view of the recording machine. Fig. 8 is a sectional view of a de-

tail. Fig. 9 is an end elevation of the recording machine. Fig. 10 is a side elevation of one end of the recording machine. Fig. 11 is a transverse section of the recording machine taken on the line 11 in Fig. 3 looking in the direction of the arrow. Figs. 12 and 13 are elevations of a relay. Fig. 14 is a cross section of the workmen's timed recording switch box. Fig. 15 is a bottom view of a portion of the upper part of said box. Fig. 16 is a side elevation thereof. Fig. 17 is a top plan view of the same box. Fig. 18 is an elevation of a governor. Fig. 19 is a perspective view of a rotating momentary contactor. Fig. 20 is an elevation of a gage or indicator. Fig. 21 is a longitudinal section of an oscillatory momentary contactor. Fig. 22 is an elevation of a clock face. Fig. 23 is a perspective view of a hand for the clock. Fig. 24 is a perspective view of a vibratory contactor, and Fig. 25 is a perspective view showing the contactor applied to a steam whistle.

I will first proceed to describe my invention in a general way, having particular reference to the diagrammatic representation in Fig. 1 and the sample record sheet shown in Fig. 2. After having described the system as a whole, I will then proceed to take up in detail the structure of the various elements of apparatus employed, and explain them more particularly than can be done in connection with Figs. 1 and 2.

The record sheet 21 is fed along by clock-work, (not shown in Fig. 1) in the direction of the arrow. An anvil 22 is pivoted on a horizontal transverse axis above the record sheet 21. This anvil is shown in perspective detail in Fig. 4. Directly below the axis of the anvil 22 in the same vertical plane with said axis is a series of vertical plungers 23, 23', 23'' adapted to push the record sheet 21 up against the anvil 22. Between the record sheet 21 and the anvil 22 is an ink ribbon 24, and the anvil carries several rows of type 25, 25^a, 25^b, 25^c, so that an upward thrust on any one of the plungers 23 will push the paper 21 against a type of one of these type-rows 25, the ribbon 24 intervening, and will therefore cause the paper 21 to receive an impression from the type. As shown in Fig. 2 the record sheet 21 is marked in parallel longitudinal alternating numbered columns and

lines, and for each of these there is a plunger 23. The numbers of the columns and lines are designated *v*. Corresponding to each plunger 23 is a magnet 26 adapted, 5 through its armature 27, to actuate the plunger. At this point I will mention that in circuit with each magnet 26 is some piece of apparatus or some indicator and that a closure of any circuit by its apparatus or 10 indicator causes a record to be made on the record sheet 21. This record sheet 21 is marked with minutes, as shown by the reference character *w* in Fig. 2, so that the time of the recorded event is at once apparent on 15 inspection of the record sheet. For certain purposes it may be desirable to indicate different characters on the record sheet, so as to differentiate the events which cause those characters to be imprinted. This is done 20 by rotating the anvil 22, and thus bringing different sets of type 25 above the plungers 23.

A crank arm 28 (broken away in Fig. 1) hangs down from the anvil 22 and carries 25 an armature 29 at its lower end. When this arm 28 hangs straight down the type 25 then in position, are adapted to print dots. Magnets 30, 31 and 32 are arranged to act 30 on the armature 29, and thus bring other type 25^a, 25^b or 25^c in registering position above the plungers 23. When the armature 29 is drawn to the magnet 31, dash type will 35 be brought in registry with the plungers 23. Energization of the magnet 32 will bring 40 double dash type into action, and the magnet 30 will bring circle type in active position.

Having described the most essential elements of the recording machine, which is represented generally as A, I will now describe 40 the circuit closers which cause the circuits leading to the machine A to be energized. 33 represents a lever adapted to start a machine to operate. For example, this lever 45 33 may be the lever which controls the clutch for a belt wheel, from which a belt leads to a machine represented generally by B, as for example a reciprocating saw. When the lever 33 is thrown so as to cause 50 the machine B to operate, the contact 34 will be closed, and thus the current will flow from the battery 35 through the main conductor 36 to the relay magnet 37, and thence through the closed contact 34 and 55 conductor 38 and through the contacts 39 and 40 back to the battery 35.

The governor 41 is intended to be driven by the factory engine, or from any shaft which is in motion while the factory as a 60 whole is operating. Thus, when the factory is operating, as during the daytime, the governor 41 will take a position so as to close the contact 39. But, when the factory is shut down, as at night, the governor will 65 take a position that will open the contact 39.

The wiper 43 rotates slowly, making for example, one revolution per minute; thus, it follows that when the contacts 39 and 34 are closed a complete closure of the circuit through the relay magnet 37 is effected 70 momentarily once each minute by the closure of the contact 40. It is to be noted that if the wiper 43 should stop in a position to close the contact 40, the circuit would not remain closed, because at the same time the governor 75 41 would be stopped, and this would cause the circuit to open at 39. Once in each revolution, the wiper 43 opens the contact 42 for an instant only. The purpose of this will be explained later. 80

It will now be seen that when the factory is in operation, and when the particular machine B controlled by the lever 33 is running, the relay magnet 37 will be energized 85 momentarily once a minute. This will cause a momentary closure of the contact 44 which will close a circuit traced as follows: from the battery 35 along the main conductor 36, through the contact 44, back over the conductor 45, through contact 65 and magnet 90 26, thence by the conductor 46, through the contact 47, over the conductor 48, back to the battery 35. It follows that once a minute the magnet 26 will be energized, thus by means of the plunger 23 pushing the paper 95 21 against the dot type 25. It is therefore apparent that once a minute the record paper will have a dot imprinted thereon. A series of dots spaced at one minute intervals on the record sheet, as shown at *m* in Fig. 2, 100 indicates that the machine B corresponding to column 4 on the record sheet is running. If the dots are spaced wider apart than at one minute intervals, this shows that the machine B is running slow. But, in addition to showing whether the machine is running, I have arranged apparatus to indicate whether it is running idle, or is doing effective work. Assume, for example, that the machine having the control lever 33 is a 105 rotary saw mounted to be oscillated manually on a pivotally suspended arm. I attach an oscillatory momentary contactor to the supporting arm, and thus the circuit is closed only when the saw is being reciprocated by 110 the workman in charge of it. This device is fully illustrated in Fig. 21. I will here state that it consists of a tube 49 containing mercury 50, and that each oscillation of the tube 49 causes the mercury 50 to electrically 115 connect the terminal conductors 51 and 52. This has precisely the same effect as the closure of the contact 44, but occurs irregularly, so that the dots will appear on the paper 120 irregularly as at *z* in Fig. 2. Such an irregular series of dots indicates not only that the machine is running, but that it is doing effective work, whereas the regularly spaced dots as at *m* indicate that the machine is 125 running idle. 130

In multiple with the contacts 44 and 51—52 is a watchman's push button 53. It is obvious that if the machine were running, a push on this button would simply introduce 5 an additional dot on the record sheet 21 among those already described. But, at night when the machine is idle there will be no such dots as *m* or *l* and therefore the dot made by the watchman pushing the button 10 53 will stand alone as indicated at *b* in Fig. 2.

The apparatus represented generally by the letter C is similar to that represented by B, the relay magnet 37' being in multiple 15 on the same circuit with the relay magnet 37. The contact 44' is in series with the recording magnet 26' through the conductor 45', this circuit being completed through the battery 35 in multiple with the circuit already traced from the contact 44. Without 20 further explanation, it will at once be obvious that when lever 33' is in running position, the contact 44' will close at one minute intervals and cause corresponding dots on 25 the recording sheet 21, but these dots will lie in a row at one side of those caused by the contact 44 and will thus indicate a different machine. Supposing, for example, that the machine C is a planer; when it is 30 running idle the idler rolls will stand still, but when lumber is being fed through, these same rolls will rotate. On one of these rolls I attach a rotating momentary contactor, indicated generally by the reference numeral 35 54, and more fully illustrated in Fig. 19. When it is revolving the mercury 55 makes frequent momentary contacts between the ring 56 and the shaft 57, thus producing 40 repeated closures of the circuit through the magnet 26', and thus making a dense series of more or less irregularly spaced dots on the paper, thereby indicating that the machine is working effectively.

A vibratory contactor 53' is shown in the 45 same relation to the machine C as the button 53 bears to machine B. This vibratory contactor may be placed for example in the floor where the watchman is expected to walk on his round through the factory, 50 and he will thus involuntarily close it just as he voluntarily closes the button 53, and with the same effect. This vibratory contactor is illustrated in Fig. 24.

A vibrating tongue 58 is attached to the 55 whistle 59, so that when the whistle is blown the contact 60 is intermittently closed, thus completing a circuit through the recording magnet 26''. This produces a series of closely positioned dots *a*, *h* or *u* in Fig. 2. 60 By their position in a certain line or column of the record sheet 21 they indicate that they relate to the whistle, and by their position longitudinally on the sheet they show the time at which the whistle was blown. I 65 have mentioned two uses for a vibratory

contactor as at 53' and 58—60, but it will be obvious that these are merely examples and that many other applications may be found for them in the general system.

Inasmuch as the whistle will ordinarily 70 be blown at comparatively rare intervals, I make use of the same recording magnet, circuit, and line or column on the record sheet, to indicate when the factory engine or other prime mover is running. As previously 75 explained, at such time the contact 39 is closed continuously, and the contact 40 is closed at one minute intervals, thus energizing the relay 37'', closing the contact 44'', energizing the magnet 26'', and imprinting 80 the regular one minute interval dots *k* in the appropriate column of the record sheet. It will be noted that the relays 37, 37' and 37'' 85 produce like effects in their respective lines or columns of the record sheet 21, except that 37 and 37' act only when the contacts 34 and 34' are closed, whereas 37'' is permanently connected to the conductor 38. The whistle and associated apparatus are represented generally by the letter D. 90

It is to be understood that the machines represented by the reference letters B, C and D are shown by way of example, and that other machines, differing more or less in detail and perhaps carrying other kinds 95 of contactors might be similarly connected to other magnets 26, so as to produce their independent records in other columns or lines of the record sheet 21.

In addition to the foregoing function of 100 recording the performance of the machines throughout the factory, my apparatus includes workmen's time-recording mechanism and circuits. The switch box for this feature is fully illustrated in Figs. 14 to 19 and 105 is represented generally in Fig. 1 by the letter E. It has a series of switch levers 61, 61', 61'' and 62, all of which are so arranged that they can be thrown from one side to the other only when the cover 63 of the box is 110 raised. Each switch 61 is appropriated to a particular workman and the switch 62 has two positions, respectively, designated as "in" and "out." Preferably each machine in the factory has a number and is connected 115 to record in the like numbered column of the record sheet, also the workman in charge of each machine has the same number, and he is expected to use the switch 61 bearing that number. Thus his own time record and the 120 record of his machine will appear in one column of the record sheet. When the workman comes into the factory, he raises the cover 63, and if the switch lever 62 is not already at the "in" position, he throws it 125 over to that position. The act of raising the cover 63 also raises the insulating bar 64 which carries various contact members, as shown. It will at once be apparent that when the cover 63 is raised, the contacts 65, 130

65', 65'', 66 and 67 will all be opened, while the two contacts 68 will be closed. Thus, when the cover 63 is raised, the machines B, C and D are put on open circuit by the breaking of the contacts 65, and one or the other of the two magnets 31 and 32 is energized by the closure of the contacts 68, the circuit from the battery 35 being traced as follows: conductor 48, magnet coil 31 or 32, contact 10 68, switch 62 and conductors 69 and 36 back to the battery 35. Hence when the cover 63 is raised, the armature 29 will be drawn over so as to bring either the type row 25^a or 25^b in registry with the row of plungers 23. 15 The type 25^a are adapted to print double lines which mean "out," while the type 25^b are adapted to print single lines which mean "in." See *g* and *s* in Fig. 2. Having raised the cover 63, and if the switch 62 is not 20 already at the appropriate position, having thrown it to that position, the workman swings a particular one of the switches 61 which has a number appropriated to him, and thus momentarily closes the corresponding 25 contact 70. This energizes the corresponding magnet 26 and prints "in" or "out" characters on the paper, the circuit being traced as follows: conductor 48, contact 47, conductor 46, magnet 26, contact 70, 30 switch 61 and conductors 69 and 36 back to the battery 35. Thereafter, the workman closes down the cover 63 insuring a break in the contact 70 and restoring the various contacts on the insulating bar 64 to the position 35 shown in Fig. 1. An inspection of Fig. 2 shows the "in" marks *g* for about two dozen workmen at the beginning of the day and their "out" marks at the end of the day. Of course, when the machine is actually operating 40 for time recording purposes, that is, when the cover 63 is raised, its operation for recording the performance of the machines B, C and D is interrupted, but these intervals are so brief as to create no objection. 45 In addition to the functions already described, the apparatus disclosed has mechanism and circuits for recording the readings of indicators for gages. For example, 71 and 71' represent steam gages, while 72 and 50 72' indicate temperature indicators. One of these will be described somewhat in detail, and this will suffice for all of them. See in this connection Fig. 20. Metallic sectors 73, 74, &c., are insulated from one another and arranged in a circumferential row on the dial face of the steam gage 71. From each sector 73, 74, &c., conductors 73 lead the respective conductors 45 and thence to 55 respective magnets 26. As will be seen in Fig. 20 each sector 73, 74, etc., corresponds to ten pounds of added steam pressure. The pointer 76 of the steam gage 71, is electrically connected to two opposite contact terminals 77 and 78 on the clock face 79, 60 (see Figs. 1 and 22) this clock preferably 65

being the same as the one which drives the recording sheet 21. This clock 79 has its hand 80 electrically connected through the contacts 66 to the battery 35. The same branch conductor 75 which goes to the segment 73 on the indicator 71 has similar branches in multiple going to corresponding segments on all the other indicators, thus connecting one set of corresponding segments 73, 74 to one conductor 45 and magnet 26. Other sets of segments 73, 74 are connected similarly to other magnets 26. Around the periphery of the clock face 79 are arranged other pairs of contact terminals, similar to 77 and 78, from which conductors lead, respectively, to the pointers of the various indicators 71', 72 and 72'. Opposite each of the contact terminals 77, 78 are other contact terminals 81, all connected together electrically and thence connected through the contacts 67 to the relay magnet 82, from which the conductor 83 leads to the battery 35. 80 85

Having described the structure of the additional apparatus necessary for recording 90 the readings of indicators and gages, I will now describe how this feature of my invention works. When the clock hand 80 touches the contacts 77 and 81, two circuits are closed as follows. (1) From the battery 35 over the conductor 83 through relay magnet 82, contact 67, contacts 81, 80, contact 66, back to the battery 35, thus causing a closure of contact 85—86 as will be explained more fully later. (2) From the battery 35 100 through the conductor 84, contact 66, contact 80, 77, indicator hand 76, segment 74, conductor 45', contact 65', magnet 26', conductor 46, armature lever 85, contact terminal 86, conductor 83, back to battery 35. 105 It will be observed that the closure of the first mentioned of the two circuits energizes the relay 82, thus completing the second circuit at 85—86. But, before the contact 85—86 is closed, the contact 87 is closed, 110 hence the magnet 30 is energized and immediately thereafter the magnet 26' is energized by the closure of contact 85—86. The energization of the magnet 30 attracts the armature 29 to a position where it brings the 115 circle type 25^c in registry with the plungers 23. The ensuing energization of the magnet 26' prints a circle on the paper 21. The position of this circle transversely on the paper corresponds to the particular segment 74 of the segments 73, 74, &c. Thus, for example, the circle designated *f* in Fig. 2 indicates a steam pressure of from seventy-five to eighty-five pounds. If the pressure had lain between eighty-five and ninety-five 125 pounds, the pointer 76 would have made contact with the next segment on the steam gage 71, and thus the next magnet 26 would have been energized and the circle would have been printed a half column to the right 130

of where it appears in Fig. 2. The particular indicator which sends in its record is shown by the abbreviations "Pres 1," "Tem 1," "Pres 2," "Tem 2" printed on the right 5 of record sheet 21. Inasmuch as the conductors leading from the hands of the various indicators 71, 71', 72, 72', go to contact terminals placed at different points around the clockface 79, it will be seen that these 10 records occur in succession for the various indicators 71, 71', 72 and 72', and hence the records appear in cyclic order on the paper 21 and are therefore indicated by the abbreviations, as just stated. Thus, the circle 15 *c* means that at forty-nine minutes past the hour the temperature indicator number 2 had a temperature of approximately 90° F.

Referring particularly to Fig. 2, which 20 represents a sample record made by the apparatus as described, I will now point out the interpretation of the various recorded marks thereon. The record sheet moves under the printing type 25 in the direction indicated by the arrow *F*. During the night 25 as the watchman goes from one station to another operating in succession the various buttons or vibrators 53, 53', the dots *b* are produced thereby, thus giving a record of his movements. It will be noticed that the 30 series of dots *b* ends at the right of the sheet and recommences at *d* at the left of the sheet as the watchman passes from push button No. 24 back to No. 1. The absence of the dot at *e* indicates a failure to push 35 the button No. 3.

The close irregularly positioned dots *a*, *h* and *u* indicate when the whistle was blown. The small circle *c* indicates that at forty-nine minutes past eight o'clock, temperature 40 indicator No. 2 showed a temperature of approximately 90° F. The circle *f* means that at fifty-six minutes after eight o'clock, pressure indicator No. 2 showed a pressure of approximately eighty pounds and similarly for the other circles.

The double dashes *g* indicate when the 45 various workmen recorded their presence on entering the factory,—for example, this record shows that workman No. 10 entered at about five and one half minutes after eight o'clock. The absence of any double dash at *i* shows that workman No. 15 did not report.

The spaced dots *j* indicate where machines Nos. 1, 2, 3 and 4 started and ran 50 idle for a few minutes. *m* indicates that machine No. 4 continued to run idle for a considerable length of time. The closely 55 positioned irregularly spaced dots *l*, *z*, &c., show where machines were running and doing useful work. The spaced dots *o* and *p* indicate a temporary cessation of useful work by machines 1 and 3. The memorandum "Out of material" and "Sharpening tool" indicate the excuses given by the 60 65

workman, and written in by an attendant on the record sheet. The regularly spaced dots *k* indicate when the factory, as a whole, was running. The breaks at *q* and *r* show when the factory, as a whole, was shut down. 70 The wider spacing at *y* indicates that the engine was running slowly, and the memorandum "Hot crank pin" explains the reason. The single dashes *s* indicate the times at which the workmen registered on leaving 75 the factory. It will be noted that there is a blank at *t* for workman No. 15.

While I have distinguished the idle operation of a machine from the useful operation thereof by recording an irregular 80 closely positioned series of dots for the former and regularly spaced dots for the latter, it will be obvious that the distinction might be made in other ways. For example, the momentary contactors illustrated 85 in connection with machines B and C might make very regularly spaced dots, the series being distinguished from the widely spaced dots only by the greater frequency.

To illustrate the great utility of the combined record made by this apparatus, I mention the following hypothetical example. An unusually wide spacing of the dots on the record sheet at 7:15 in the morning indicates that the engine was running at only 95 half speed. Also the record shows that a certain employee registered in at 7:10 a. m. and at 7:12 he has his machine running at the slow speed, but not producing work. An investigation as to the cause of this may 100 be made on the record sheet itself, for it will disclose that at this time the boiler pressure was only eighty pounds when it should have been one hundred pounds, and an hour previously the temperature recorder indicates that there was no fire in the boiler 105 furnace. Also the record shows that no whistle was blown at six o'clock in the morning and that the watchman had not been on duty since three o'clock in the 110 morning. Knowing that it is the duty of the watchman to start the fire in the furnace at five o'clock, it may be inferred that all the irregularities noted are due to his delinquency. When the fireman came on duty 115 there was not enough steam in the boiler to blow the whistle, and hence the employee had an excuse for oversleeping and being late. The employee's machine is not doing useful work, because the engine is running 120 too slow, and the engine is running slowly because of insufficient boiler pressure.

Having described my system in a general way, and having discussed the work accomplished thereby, I will now take up certain 125 of the elements of the apparatus and describe them somewhat in detail. The recording machine, represented generally, in Fig. 1 by the letter *A*, is illustrated in Figs. 3 to 11 inclusive. On the base 88 stand the 130

legs 89 supporting the table 90, which has guide flanges 91 at its sides. At one end is a feed paper roll 92 rotatably mounted in brackets 93, from which the paper 21 passes to the top of the table 90 going around the curved end 94. There is an opening 96 in the table 90, projecting up through which is an idle roller 97 carried on the arm 98, which are pivoted on the shaft 99. The depending arm 100 is adjustably engaged by the tension spring 101 and thumb screw 102, thus tending to push the roller 97 up against the opposed roller 103, the latter being carried by the shaft 104 which is mounted in the brackets 105. This shaft 104 is driven or controlled in its rotation by the clock 106, the milled head 107 being also provided so that the shaft can be turned by hand when desired. A catch 102^a is provided to lock the idle roller 97 down when that may be desirable for the purpose of manipulating the record paper 21. The two rollers 97 and 103 preferably have their peripheries roughened, which causes them to tightly engage the paper 21 and feed it from the roller 92 lengthwise across the table 90. At the opposite end of the table the paper 21 passes around the idle roll 108 and thence to the winding drum 109.

Within the drum 110 is a clock spring having one end attached to the shaft 111 and the other end attached to the gear wheel 116. The end 112 of the shaft 111 is adapted to be engaged by a key for winding the said spring. A ratchet 113 on the shaft 111 and a pawl 115 on the standard 114 serve to keep the spring wound so that its tendency is to rotate the gear wheel 116, thus tending to rotate the winding drum 109 through the intermediate gears 117 and 118. The intermediate gear wheel 117 has a shoulder on its shaft 119, and against this shoulder a belt pulley 120 is clamped by means of the screw 121 and the clamp nut 122. The band 123 passing from the pulley 120 goes to the pulley 124 on the shaft 125. The ribbon 24 has one end adapted to wind upon the shaft 125, while the opposite end unwinds from the idle shaft 127, the intermediate part of the ribbon passing under the two idle rollers 126 close to the paper 21. The ribbon shaft 127 has a milled head 128 with a crank 129, so that after the ribbon is wound upon the shaft 125 the pulley 120 can be released by loosening the nut 122, and then by means of the handle 129 the ribbon can be wound back upon the shaft 127.

The paper winding drum 109 is made removable, one end fitting upon the shoulder 131 which is carried by the shaft 130 of the driving gear 118. This shaft also carries a ratchet wheel 132, which is adapted to be engaged by a dog 133. At its opposite end the winding drum 109 has a point 134 adapted to be engaged by a socket in the end of

the sliding bar 135, the latter being held in place by the spring 137. The bar 135 has a head 136 by which it may be withdrawn in order to introduce or remove the winding drum 109.

The spring in the drum 110 tends to rotate the winding drum 109 in a direction to keep a tension on the paper 21. Hence when the drum is removed, or when it is desired to slacken the paper 21, the dog 133 is provided so that it can be thrown over in engagement with the ratchet 132, and thus prevent rotation of the gear wheel 118.

At one side, near one end, the table 90 has a horizontal extension 138^a, on which is pivoted at 139 a leaf 138 adapted to swing inwardly above the table 90. It will be observed that the paper passes a considerable distance after it receives its record at 22 before passing around the idle roller 108. Thus the recent record on the paper is easily visible upon the table 90 and if it is desired to make any memoranda the leaf 138 can be swung across so as to afford a rest for the hand. It will be noted that the corner 140 of the leaf 138 is rounded, so as to avoid interference with the flange 91. Directly above the paper 21 and the ribbon 24 is the anvil 22 which is shown inverted in perspective in Fig. 4. Directly below the axis of the anvil 22 is a series of holes 141 in the table 90, which serve as guides for the upper ends of the plunger 23, the cross bar 147 acting as a lower guide. A soft iron plate 142 is fastened under the table 90, and to this the pole pieces of the magnets 26 are attached by means of the screws 143. The armatures 27 of the magnets 26 are pivoted in two series at the sides upon the horizontal shafts 144. An inspection of Fig. 6 will show that the magnets are staggered, and that the ends 146 of the armatures 26 lap past one another, so that a very close arrangement of the plungers 23 is secured and yet space is found for the magnets 26. The transverse bars 145 constitute back stops for the armatures 127. Figs. 3, 7 and 11 show the magnets 30, 31 and 32, all having a common soft iron yoke plate 149 supported by the side frame 148.

The relay designated as 82—85 in Fig. 1 is illustrated in Figs. 12 and 13. On the base 150 is the yoke 151 which carries the magnet coils 82. The armature 85 is carried by a pivoted arm 155. This arm 155 is connected to the conductor 46 and carries one member of the contact 47, the other being carried by the fixed standard 156. Attached by insulation 157 to the extremity of the arm 155 is a conductor terminal 158, being one member of the contact 87. Thus, it will be seen that when the armature 85 is attracted, first contact 47 is broken, second contact 87 is closed, and third contact 86 is closed.

I will now describe the workmen's time re-

cording switch box as illustrated in Figs. 14 to 17 inclusive. The switch box comprises two superposed sections 160 and 161, hinged together at 162. The upper section has a bottom 161^a with openings 161^b therethrough. The handles of the switches 61 and 62 (see Fig. 1) project up through these openings 161^b. In the lower compartment 160 are the contact terminals 70 which are engaged by the buttons 61^a when the handles 61 are thrown. The various switches or contacts 65, 65', 65'', 66 and 67 are of the knife blade switch type shown in Fig. 14. All these knife blade switches 65 are pivoted at 166 and carried by the insulating bar 64 which is connected to the hinged cover 63 of the box by means of the link 164,—this link having pin and slot connections 163 and 165 at its ends. Thus, it will be seen that when the cover 63 of the box is opened, the knife blades 65 will be raised and the switches opened. However, at this time the contacts 68 will be closed, see Figs. 14 and 16. The two contacts for the switch 62 are designated 167 in Fig. 15.

The governor and the periodic (one minute) circuit closure are shown in Fig. 18. The collar 168 rises when the centrifugal force of the balls throws them out compressing the spring 169, but when the balls do not rotate, their weight and the spring 169 act together to force the collar 168 down. The tension spring 173, acting on the knife blade 172, pushes the plunger 171 up against the lever 170, keeping the blade 172 in the jaws 174, and thus closing the contact 49 when the collar 168 is up, that is, when the balls 41 are being rotated by the driving pulley 175. But, when rotation ceases the collar 168 will fall and push the blade 172 out from the jaws 174, this breaking the contact 49. The shaft of the pulley 175 carries a worm 176, which engages the worm wheel 177, thus rotating it slowly. The arm 178 is held in the position shown in Fig. 18 by the tension spring 179, but in each revolution the stud 43 on the worm wheel 177 pushes the arm 178 over so that the spring terminal 180 closes the contact 40. The circuits through the magnets 26 are broken at 42 for an instant only, once in each revolution of stud 43. The purpose is to release the paper 21 in case it is held back by the pressure of plungers 23.

I will now describe the rotating momentary contactor shown in section in connection with machine C in Fig. 1. This is shown in perspective partly broken away in Fig. 19. The metal ring 56 is clamped between insulating disks 181, and the insulating sector shaped blocks 182 are arranged as shown. As the device rotates the mercury 155 in flowing between the insulating blocks 182, and the central shaft 57 will establish a metallic connection between said shaft and

the ring 57. However, it will be seen that this connection is necessarily intermittent, because if the device stops rotating the mercury will not rest permanently against the shaft 57.

I will now describe the oscillatory momentary contactor illustrated in Fig. 21 and indicated diagrammatically at B in Fig. 1. A metal block 49 has two holes 49^a drilled in from the ends and meeting at an angle. The ends of these holes are closed by studs 51 and the conductor 186 is attached at 187 by means of solder. Through insulating bushings 189, the screws 52 pass into the chamber 49^a. The conductor 188 is attached to these screws by lock nuts 189. It will be seen that when the block 49 is oscillated laterally, the mercury 50 will be shot over from one side into the other, its contour being somewhat as indicated by the dotted lines in Fig. 23. At such time, the mercury will establish a metallic connection between the blocks 49 and one of the screws 52.

Fig. 20 shows a steam gage with the insulated metallic segments 73, 74 arranged to be touched in succession by the index or pointer 76. This illustrates how the gages 71, 71', 72 and 72' of Fig. 1 are constructed.

Fig. 22 shows the arrangement of the contact terminals 77, 78 and 81 in the clock face 95 79. The various conductors connecting these terminals are arranged on the back side of the clock face, which is preferably made of fiber or other insulating material.

Fig. 23 shows the long hand of the clock 100 with contact wipers 191 attached thereto.

Figs. 24 and 25 show the vibrator as attached to the steam whistle. 192 is a small slab of insulating material through which the adjustable contact point 60 passes. The 105 vibrating tongue 193 carries a weight 58 at its end and the adjustment of the screw 60 is such that the slight vibration of the tongue 193 will cause it to touch the screw 60, and thus intermittently close a circuit.

It will be readily understood that many variations can be made in the detail arrangements of this apparatus, without departing from the invention herein disclosed and claimed. I will mention a few examples of such changes that might be made. It may be found desirable to substitute a star wheel coating with a series of perforations in the record sheet 21 in place of the two wheels 103 and 97, which engage the 120 paper frictionally. It may be desirable in some cases to arrange the contact 34 on the lever 33 so that the circuit will be closed when the lever is in the "off" position. In this case it would be necessary to change the 125 contact 44 so that it would close on the back stop of the relay instead of on the front stop. For the sake of avoiding obscurity, I have frequently employed specific terms in the following claims. For example, I men- 130

tion the contact 33, as a "starting lever." But I desire to have it understood that in this case and in similar cases I mean to include under such a term all equivalents.

5 For example, under the term "starting lever," I mean to include any element whose condition is changed when the machine B is running, as compared with when it is idle.

In many instances the dots impressed on 10 the record sheet by the plunger 23 are made so frequently that they merge together in one continuous straight line, but for the sake of clearness in explanation, I have shown more or less spacing in Fig. 2. If it 15 should happen that the circuit of any magnet 26 became permanently closed, this would hold the paper fixed between the corresponding plunger 23 and the type anvil 22, and the paper would buckle between this 20 point and the drive roller 104. But, by opening all the circuits of the magnets 26 at 42 once every minute, this effect is prevented from becoming cumulative.

The circuit is broken at 47 before it is 25 made at 87, in order to be sure that no plunger 23 will be in engagement with the type anvil 22 when the anvil is shifted. Thereafter the circuit is closed at 86, thus 30 reversing the connection of the battery 35 in its connection to the magnets 26. While the contact 86 is closed, any closure of a momentary contactor at C will momentarily short-circuit the battery 35, the circuit being traced as follows; from battery 35 over 35 conductor 84, through contact 66, contact 80-77, contact 76-74, conductor 45', back through momentary contactor at C, and thence by a conductor 36 back to battery 35. This short-circuiting of the battery will 40 momentarily release plunger 23', but inasmuch as the contact 80-77 is maintained for at least several seconds, the plunger 23' will be sure to make its record.

It will be observed that the apparatus is 45 so arranged that no plunger 23 presses for any considerable length of time against the anvil 22, and thus the proper feeding of the paper 21 is not interfered with.

In the following claims I have referred to 50 "a rectangular array of type" meaning an arrangement of type in rows and columns. A reference to Fig. 4 of the drawings shows an example of this.

I claim:

55 1. In recording apparatus, means to give a record sheet a substantially continuous movement, type adapted to print at definite positions on said sheet, means to print from said type in accordance with certain conditions which it is desired to have indicated, and means operative at any time and at once to vary the character of a type in a particular position so as to further distinguish the indications on the record sheet.

2. In recording apparatus, clock mechanism to drive a record sheet, type adapted to print at definite positions on said sheet, means to print from said type in accordance with certain conditions which it is desired to have indicated on the sheet, and means 70 operative at any time and at once to vary the character of a type in a particular position so as to further distinguish the indications on the record sheet.

3. In recording apparatus, means to give 75 a record sheet a substantially continuous movement, a series of type arranged transversely in printing position near said sheet, means to print from particular type in accordance with certain conditions which it is desired to have indicated on the record sheet, and means operative at any time and at once to vary the character of a type in a particular position so as to further distinguish the indications on the record sheet. 80

4. In recording apparatus, means to give a record sheet a substantially continuous movement, a series of type arranged in printing position across said sheet, means to print from particular type in accordance 90 with certain conditions to be indicated on the sheet, additional type in proximity to said first mentioned type, and means operative at any time and at once to substitute said additional type for the others so as to 95 further distinguish the indications on the record sheet.

5. In recording apparatus, means to give a record sheet a substantially continuous movement, a type anvil adjacent to said 100 sheet, said anvil having parallel rows of type extending transversely to the direction of movement of the sheet, the type in different rows being different, means to shift the anvil so as to bring a particular row of type 105 into printing position in accordance with a particular class of conditions to be indicated, and means to print from a particular type in the selected row in accordance with the condition to be indicated. 110

6. In recording apparatus, means to give a record sheet a substantially continuous movement, a rectangular array of type near 115 said sheet, means to shift said array so as to bring a particular row thereof into printing position in accordance with conditions to be indicated on the paper, and means to print from a particular type of the selected row so as to still further distinguish the indications on the record sheet. 120

7. In recording apparatus, means to move a record sheet uniformly in one direction, a plurality of printing plungers arranged transversely across said sheet, corresponding electromagnets to actuate said plungers, circuits for said magnets, condition indicating circuit closers in said circuits, a plurality of rows of type adapted to be actuated by 125

said plungers, means to change said rows of type, and means to simultaneously shift the circuit connections to other condition indicating circuit closers.

- 5 8. In recording apparatus, means to give a record sheet a substantially continuous movement, a plurality of printing plungers arranged transversely to the sheet, respective electromagnets therefor, a plurality of 10 type adapted to be actuated by each plunger, a plurality of branch circuits adapted to be connected to each magnet, and means to simultaneously change the type and to correspondingly change the connections to the 15 branch circuits.

9. In recording apparatus, means to give a record sheet a substantially continuous movement, a rectangular array of type near said sheet, a single row of printing plungers 20 with respective mechanisms to actuate them, various elements having possible conditions to be indicated by each plunger, means to connect said elements individually to the plunger mechanisms and at the same time to 25 shift the type array correspondingly.

10. In recording apparatus, means to give a record sheet a substantially continuous movement, a rectangular array of type adapted to print at definite positions on said 30 sheet, machines, gages, time recording apparatus, a row of type in the array corresponding to each of said three classes of elements, means to respectively connect any one element of a class for printing and thereby indicating its condition, and means to shift the said type array so as to bring a corresponding row of type into printing position.

11. In recording apparatus, means to give a record sheet a substantially continuous 40 movement, a series of printing plungers arranged near said sheet, an electromagnet for each plunger, machines, gages and workmen's time recorders with circuits adapted to be connected to said magnets, type adapted to be changed, and means to change said type in accordance with a change in the class of apparatus connected to the magnets.

12. In recording apparatus, means to give a record sheet a substantially continuous 50 movement, printing mechanism, electromagnets to actuate the same, various machines, means to print spaced characters on the sheet when the machines are running idly, and means to print said characters differently 55 spaced when the machines are performing useful work.

13. In recording apparatus, means to give a record sheet a substantially continuous movement, a row of printing plungers arranged across the sheet, an electromagnet for each plunger, various elements of apparatus whose condition is to be indicated by the respective plungers, means to actuate said plungers at certain definite intervals

to indicate one condition of each of said elements, and means to actuate said plungers at different intervals to indicate a different condition.

14. In recording apparatus, means to give a record sheet a substantially continuous movement, means to print rows of characters on said sheet as it moves, various elements of apparatus corresponding to the different rows of characters of the sheet, means to print said characters at definite 75 spaced intervals when said elements are in one condition, and means to print the same characters in the same rows with a different spacing when in another condition.

15. In recording apparatus, means to give a record sheet a substantially continuous movement, printing plungers arranged across the sheet, respective electromagnets to actuate the same, various elements of apparatus whose condition is to be indicated, two 85 alternative branch circuits from each electromagnet to each said element of apparatus, one branch including a regularly timed intermittent circuit closer to indicate one condition of the element, and the other branch circuit including a circuit closer having a different time rate to indicate another condition of the element.

16. In recording apparatus, means to give a record sheet a substantially continuous 95 movement, a row of printing plungers arranged across said sheet, respective electromagnets therefor, a circuit for each electromagnet, each said circuit having a plurality of branches, variously timed circuit closers 100 in the respective branches, and means to actuate each circuit closer in accordance with a particular condition of some piece of apparatus which it is desired to have indicated.

17. In recording apparatus, means to give a record sheet a substantially continuous movement, a row of plungers for printing on said sheet, respective electromagnets therefor each having an independent circuit with multiple branches, relays adapted to 105 close one branch for each magnet, a circuit to energize said relays, said circuit being closed at definite intervals, the relay magnets being in multiple in said circuit, means to close the multiple branches of the last 110 named circuit in accordance with certain conditions to be indicated, other circuit closers in other branches for each magnet, and means to actuate said last named circuit closers upon the existence of different conditions to be indicated.

18. In recording apparatus, means to give a record sheet a substantially continuous movement, a row of printing plungers in proximity thereto, respective electromagnets 125 therefor, respective circuits for the said magnets, each circuit having two branches, intermittent circuit closers for one of each

said branches, machines corresponding to each electromagnet, means to render each said intermittent circuit closer active whenever the respective machines are running, 5 and circuit closers in other branches adapted to be operated at a different frequency when the respective machines are operating usefully.

19. In recording apparatus, means to give 10 a record sheet a substantially continuous movement, a row of printing plungers across the sheet, respective electromagnets and associated circuits therefor, various machines to which the respective circuits lead with two 15 branches for each machine, control means for each machine, a relay operated circuit closer in one branch of each circuit, the energizing circuit for said relay including a periodic circuit closer, and a switch on the 20 control means of the corresponding machine arranged so that the circuit controlled by the relay will be closed only when the machine is running, the other branch to each machine having a circuit closer attached to 25 some member of the machine which operates only when the machine is doing useful work, said last named circuit closer operating at a different frequency from the first mentioned periodic circuit closer.
- 30 20. In recording apparatus, means to give a record sheet a substantially continuous movement, a row of printing plungers across said sheet, electromagnets and associated circuits therefor, each circuit having two 35 branches, one branch being adapted to be closed at intervals by a machine when running, and the other branch being adapted to be closed by manually operated circuit closers.
- 40 21. In recording apparatus, means to give a record sheet a substantially continuous movement, a printing plunger, an electromagnet and associated circuit to actuate the same, a factory whistle, and a loaded spring 45 vibratory circuit closer attached to the whistle and adapted to be operated when the whistle is blown.
22. In recording apparatus, a record sheet, 50 a printing plunger, an electromagnet and associated circuit therefor, said circuit having two branches, with a circuit closer in each branch, one circuit closer being operated intermittently by a factory prime mover when it is running, and the other circuit 55 closer being operated at a different frequency when the factory whistle is blown.
23. In recording apparatus, means to give 60 a record sheet a substantially continuous movement, a printing plunger, an electromagnet and associated circuit therefor, a machine whose performance is to be indicated, and an oscillating momentary contactor in said circuit attached to an oscillating part of the machine.
- 65 24. In recording apparatus, means to give

a record sheet a substantially continuous movement, recording mechanism comprising electric circuits, a prime mover, a centrifugal governor driven by said prime mover, a circuit closer for one of said circuits 70 adapted to be closed by the said governor at and above a certain speed, and an intermittent circuit closer in series with said first named circuit closer.

25. In recording apparatus, a record sheet, 75 means to give a record sheet a substantially continuous movement, gages, means to operatively connect the gages for recording purposes at different times, and means to indicate the reading of each gage by printing in a certain position on the record sheet.

26. In recording apparatus, a clock to move a record sheet in one direction, means to print characters in various positions across the sheet, gages adapted to be connected at certain different times so as to print on the sheet, and means to cause the printed character on the sheet to appear in a transverse position thereon corresponding to the reading of the gage. 90

27. In recording apparatus, means to give a record sheet a substantially continuous movement, printing plungers across the sheet, respective electromagnets and associated circuits, gages, a row of contact segments on each gage, like segments on all the gages being connected in multiple to a respective electromagnet, pointers on the gages adapted to make contact with said contact segments, and a clock adapted to 100 complete a battery circuit through the different gage pointers at respective times.

28. In recording apparatus, means to give a record sheet a substantially continuous movement, printing plungers, respective 105 electromagnets and associated circuits therefor, all said circuits being in multiple on one battery with a clock hand in series with the battery, gages with movable indexes therefor, contact segments arranged around 110 the clock face and connected to the respective indexes, and contact segments arranged along the various gages, corresponding segments on all the gages being connected in multiple to a single magnet circuit. 115

29. In recording apparatus, a record sheet, means to move said sheet, a set of type normally in printing position near said sheet, another set of type in proximity thereto, a magnet to shift the type, a clock, apparatus 120 having conditions to be indicated on the sheet, printing mechanism, energizing circuits leading therefrom through the said apparatus and through the clock, an actuating circuit for the said magnet leading through the 125 clock, and means associated with the clock to close both circuits simultaneously at definite times.

30. In recording apparatus, means to give a record sheet a substantially continuous 130

- movement, a set of type normally in printing position, another set of type, an electromagnet to shift the type, a clock, gages, contacts on the clock face, printing electromagnets, circuits leading through the clock hand and said contacts, one of said circuits being adapted to actuate the type shifting electromagnet and the other circuits being adapted to have one of them completed immediately thereafter through one of the gages thereby indicating its reading on the record sheet.
31. In recording apparatus, means to give a record sheet a substantially continuous movement, printing plungers across said sheet, respective electromagnets and associated circuits therefor, numbered workmen's time recording switches in the respective circuits, and type to coact with said plungers, said type being interchangeable to indicate "in" or "out".
32. In recording apparatus, means to give a record sheet a substantially continuous movement, two different rows of type across said sheet, electromagnets adapted to print from either row across the sheet, circuits therefor, workmen's time recording switches in the respective circuits, and means to throw either row of type in printing position as desired before operating said switches.
33. In recording apparatus, means to give a record sheet a substantially continuous movement, a row of printing plungers across said sheet, two rows of type across said sheet, magnets to bring the respective type rows into printing position, magnets and associated circuits for the respective plungers, means to operate the type positioning magnets, and switches in the magnet circuits.
34. In recording apparatus, means to give a record sheet a substantially continuous movement, a row of printing plungers across said sheet, respective electromagnets and associated circuits therefor, each said circuit having branches, workmen's time recording switches attached to close one branch of each circuit and interlocking means adapted to open the other branch of each circuit before permitting said switches to operate.
35. In recording apparatus, means to give a record sheet a substantially continuous movement, a row of printing plungers across said sheet, respective electromagnets and associated circuits therefor, each circuit having multiple branches, workmen's time recording switches in one branch of each circuit and interlocking means to open the other branches of the circuits before permitting any one of said switches to be operated.
36. In recording apparatus, means to give a record sheet a substantially continuous movement, printing plungers across said sheet, respective electromagnets and associated circuits therefor, each circuit having multiple branches, a box with a cover containing a switch for a branch of each circuit, the switches being closed when the cover is closed, connections from the cover to open said switch when the cover is open, the other branch having a contact within the box being adapted to be actuated independently to close the respective branch circuits.
37. In recording apparatus, means to give a record sheet a substantially continuous movement, printing plungers arranged across said sheet, respective electromagnets and associated circuits therefor, a plurality of sets of type to be actuated by said plungers, magnets to position said type, circuits therefor, a switch box with a cover within the box in the type positioning magnet circuits, said switches being connected to the cover of the box so as to be open when the cover is closed, and vice versa, other switches within the box to selectively energize the type positioning magnets, and switches within the box in the plunger magnet circuits.
38. In recording apparatus, means to give a record sheet a substantially continuous movement, a row of type printing plungers across the sheet, respective electromagnets and associated circuits therefor, a box with a hinged cover, switches for said circuits within the box, an insulating beam within the box, connections therefrom to the cover, other switches for other circuits connected to said insulating beam and adapted to be shifted by opening the box cover, thereby putting the apparatus in condition for shifting the first mentioned individual circuit switches.
39. In recording apparatus, electrical circuits, branch circuits, workmen's time recording switches adapted to close said branch circuits, a box containing said switches, other switches within the box, a cover for the box, connections from the cover to said other switches to throw the same when the cover is opened and closed, and thus change the various circuit connections to correspond with the accessibility of the workmen's switches within the box.
40. In recording apparatus, clock mechanism to move a record sheet, means to print substantially continuous records of certain conditions thereon, and means to print superposed records of other conditions on the sheet.
41. In recording apparatus, clock mechanism to move a record sheet, means to print substantially continuous records of certain conditions thereon, and means to print superposed records of other conditions at intervals on the sheet.
42. In recording apparatus, clock mechanism to move a record sheet, means to print

substantially continuous records of certain conditions thereon, and means to print superposed records of other conditions when the sheet is at certain definite stages of its 5 movement.

43. In recording apparatus, clock mechanism to move a record sheet, means to print on the sheet a substantially continuous record of the performance of certain numbered 10 machines, and means to print superposed time records for correspondingly numbered employees.

44. In combination, a steam whistle, a device to be actuated when the whistle is blown, an electric circuit for actuating said 15 device, and a loaded spring vibratory circuit closer for said circuit attached to the whistle.

45. In combination, a steam whistle, a device to be actuated when the whistle is blown, an electric circuit for actuating said device, an insulated leaf spring with one end weighted and the other end attached to the whistle, a contact terminal slightly 20 spaced from the leaf spring, and connections from said terminal and spring to the said circuit.

46. In recording apparatus, a clock to move a record sheet, a plurality of gages 30 adapted to be operatively connected to record on the record sheet in cyclic order, an index for each gage, a series of co-acting contact segments, and means to make a record when a gage is operatively connected 35 that shall correspond in transverse position on the sheet with the reading of the gage.

47. In recording apparatus, a clock to move a record sheet, apparatus whose condition is to be recorded, contact segments in 40 the clock face adapted to co-act with the clock hand, and connections to make a record on the sheet when the hand is in contact with one of the segments.

48. In recording apparatus, a record sheet 45 with distinguishing characters for various gages arranged in cyclic order along its length, a clock to move said sheet, contact segments in the clock face adapted to co-act with the clock hand, said segments corresponding 50 in position with the said characters on the sheet, printing mechanism in proximity to the sheet and gages electrically connected in the same order to said contact segments so as to print their records on the record sheet beside their respective distinguishing 55 abbreviations.

49. In recording apparatus, devices for recording information on a record sheet, workmen's time recording levers with means 60 to make records thereby on the record sheet, and means preventing access to said levers until the other recording devices have been previously rendered inoperative.

50. In recording apparatus, a record 65 sheet, means to move the same, apparatus

connected up to make records thereon, a workmen's time recording lever box, a cover to close the box, means to operatively disconnect the workmen's time recording levers when the cover for the box is closed, and 70 means to disconnect the other apparatus and connect the workmen's apparatus when the cover for the box is opened.

51. In recording apparatus, a table on which a record sheet lies, means to move 75 said sheet, printing apparatus at one end of the table, and a movable hand support in proximity to the table to facilitate making records manually in addition to those made by the printing mechanism.

52. In recording apparatus, a table adapted to have a record sheet to move over the same, a horizontal hand support pivoted at one side of the table and adapted to be swung across the same to facilitate making 80 records manually on said sheet.

53. In recording apparatus, means to give a record sheet a substantially continuous movement, printing mechanism in proximity to said sheet, electric circuits to actuate 90 said printing mechanism, and means to periodically open all said circuits so as to release the paper periodically.

54. In recording apparatus, clock mechanism to move a record sheet, a transverse 95 row of printing platens, and interchangeable type adapted to coact with each platen.

55. In recording apparatus, clock mechanism to move a record sheet, certain type in normal position in proximity to said 100 sheet, other type adjacent to said first named type, and means to cause said other type to take the positions of the first named type in accordance with certain classes of conditions to be indicated on the record 105 sheet.

56. In recording apparatus, means to give a record sheet a substantially continuous movement, type adapted to print at definite 110 positions on said sheet, means to print from said type in accordance with certain conditions which it is desired to have indicated, and means operative at any time and at once to produce different type impressions on the record sheet in a particular position so as to 115 further distinguish the indications thereon.

57. In recording apparatus, a recording machine, various elements of apparatus whose condition is to be recorded at the recording machine, electric circuits leading 120 from said elements to the recording machine, a prime mover coacting with the elements of apparatus referred to, and a special circuit associated with the prime mover and the recording machine to indicate the 125 performance of the prime mover.

58. In recording apparatus, a recorder, a machine whose performance is to be recorded, an electric circuit connecting the said machine and recorder, means to make a 130

straight line record corresponding to the said machines, and means to vary the character of the records in accordance with whether the said machine is running idly or 5 doing useful work.

59. In recording apparatus, a plurality of machines whose performance is to be recorded, an electric circuit connecting the said machines and recorder, means to make 10 straight line records corresponding to the respective machines, and means to vary the character of the records in accordance with whether the said machines are running idly or doing useful work.
- 15 60. In recording apparatus, means to give a record sheet a substantially continuous movement, printing mechanism, an electromagnet to actuate the same, a machine whose performance is to be recorded, means to 20 print characters on the sheet spaced in a

certain manner when the machine is running idly, and means to print the same characters differently spaced when the machine is doing useful work.

61. In recording apparatus, means to give 25 a record sheet a substantially continuous movement, printing mechanism, electromagnets to actuate the same, machines connected to said electromagnets so as to indicate their performance on the record sheet by 30 means thereof, and a prime mover connected to one electromagnet so as to indicate its performance by means thereof.

In testimony whereof I have subscribed my name.

EDWIN M. SCHANTZ.
